TYPEWRITING MACHINE

Cloyd E. Burns, Buffalo, N. Y., assignor to
 Remington Typewriter Company, Ilion, N. Y.,
 a corporation of New York

Application June 16, 1930. Serial No. 461,367

12 Claims. (Cl. 197—127)

My invention relates to typewriting or like machines and more particularly to work sheet or card holding means.

The main object of my invention, generally stated, is to provide comparatively simple yet highly effective means for supporting and maintaining a pack comprising a plurality of superposed work sheets in different positions of adjustment relatively to the printing line and in a condition where printed lines may be produced successively on the different work sheets of the pack in predetermined line space positions thereon.

A further object of my invention is to provide means of the character set forth which are in the nature of attachments that may readily be embodied in existing typewriting machines without modifying, or materially modifying, the existing structural features of the machine.

To the above and other ends which will hereinafter appear my invention consists in the features of construction, arrangements of parts and combinations of devices set forth in the following description and particularly pointed out in the appended claims.

In the accompanying drawings wherein like reference characters designate corresponding parts in the different views—

Fig. 1 is a front elevation of the carriage of a typewriting machine equipped with the devices of my invention.

Fig. 2 is an end elevation of the same with parts broken away and parts in section.

Fig. 3 is a fore and aft vertical, central, sectional view of the carriage.

Fig. 4 is an enlarged, detail, fragmentary, perspective view showing a portion of the bottom deflector and one of the spacing members secured thereto.

Fig. 5 is an enlarged, detail, fragmentary, sectional view illustrating the manner in which the pack of superposed work sheets is held in position for printing thereon.

Fig. 6 is an enlarged, detail, fragmentary, sectional view taken on the line 6—6 of Fig. 1 and looking in the direction of the arrows at said line.

I have shown my invention embodied in the present instance in a front feed Remington typewriting machine in which the devices of my present invention may readily be incorporated without materially modifying the existing structural features of said machine, as will hereinafter appear.

The carriage of the machine comprises a truck

having end bars 1, a front cross bar 2 and a rear cross bar 3. The front and rear cross bars are oppositely grooved to form race-ways which receive crossed anti-friction bearing rollers 4 by which the carriage is supported to travel over the top plate of the machine from side to side thereof. The bearing rollers 4 also are received in oppositely grooved race-ways in a front fixed guide rail 5 and a rear fixed guide rail 6. The truck supports a platen frame comprising suitably connected end plates 7 united to the truck for case shifting movement on the latter by parallel links 8 and 9. In the present instance the lower case shift screw stops 10 are adjusted up to hold the platen frame and cylindrical platen 11 carried thereby in the upper case position, upper case type only being employed in the present instance.

I prefer to employ the usual front deflector plate 12 pivoted at 13 to the end plates 7 of the platen frame and shiftable from the full line to the dotted line position represented in Fig. 3. This is in order to facilitate the introduction of the lower ends of the work sheets 14, which constitute a pack of sheets to be written on, into a space or channel 15 between a deflector plate 16 and the lower surface of the platen. In the present instance the deflector plate 16 constitutes a part of a paper table 17 provided with apertured ears 18 on the rear side thereof to receive the usual cross or tie rod 19 by which the end plates 7 of the platen are connected. Curved spacing members 20 are secured to the deflector 16 near the ends thereof and are adapted to bear against the bottom surface of the platen in order to maintain the deflector 16 spaced apart from the platen and thus provide the channel 15 referred to. Adjustable cams 21 are secured by screws 22 to the usual cross bar 23 that unites the side plates 7 of the platen frame. A loosening of the screws 22 affords a rotative adjustment of the cams on the screws, whereas a tightening of the screws 22 secure the cams in their adjusted positions. These cams bear against the bottom of the deflector 16 and maintain it positioned with reference to the platen.

In the present instance I provide the usual means for controlling the motion of the front deflector 12 from the full to the dotted line position shown in Fig. 3 and vice versa. Such means comprise a crank arm 24 (see Fig. 2) operatively connected to the deflector 12 and provided with a laterally projecting pin 25 received in a cam slot 26 of an arm 27, pivoted at 28 to a side plate 7. Two of these arms 27 are usually provided,

being connected to move together and they ordinarily constitute a carrier for a line indicating wire which, however, is omitted in the present construction. The left-hand arm 27 extends upward and terminates in a finger piece 29 for shifting the front deflector 12 from the full to the dotted line position against the force of a spring (not shown) and to hold the deflector 12 temporarily in the dotted line position shown in Fig. 3.

A link 30 is provided at its rear end with a laterally projecting pin 31 adapted to slide in a slot 32 in a bracket plate 33. The rear end of the link 30 is thus supported for movement fore and aft of the machine and has a path of movement to cooperate with the left-hand arm 27 and shift the latter forward, thereby moving the deflector 12 from the full to the dotted line position in Fig. 3. The forward end of the link 30 is pivoted at 34 to a crank arm 35 which terminates in a finger piece 36 and is secured to a rock shaft 37. This rock shaft extends from side to side of the machine and passes freely through openings in two bracket arms 38 and 39.

The bracket arm 38 is detachably connected to the carriage being provided with a foot piece 40 apertured to receive the upper case shift screw stop 41 and to be clamped in position on the carriage by a nut 42 received on the upper end of said screw stop. The stem of a headed screw 43 passes through an opening in a second foot piece 43a on the bracket arm 38 and engages in a tapped opening in the left-hand end bar 1 of the carriage. This bracket arm is apertured to receive and permit the rock shaft 37 to pass freely therethrough.

The bracket arm 39 is detachably secured to the carriage by screws 44 and is bifurcated at its rear end to straddle the tie rod 19. The rock shaft 37 ordinarily constitutes part of a controlling means for a series of paper feed rolls for shifting them into and out of effective position. However, inasmuch as there is no necessity for using these feed rolls in the present construction, they and their controlling companion devices are stripped from the shaft 37. The construction, however, is such that when the finger piece 36 is moved forward, it and the front deflector 12 controlled thereby, will be maintained in the effective dotted line position shown in Fig. 3, so as to leave both hands of the operator free to insert the pack of work sheets in the machine as will presently appear.

The construction thus far described is substantially like that employed in the Remington front feed machine except as hereinbefore pointed out and except that a single deflector plate 16 is employed instead of a double deflector plate, and there is a slight change in the manner of supporting the combined paper table and deflector plate in the present instance. Moreover, the detachable bracket arms 38 and 39 have been added to the machine by me to provide an effective support for certain of the devices of my present invention.

A supporting bar 46 is secured at its ends by screws 47 and 48 to the bracket arms 38 and 39 respectively, and is maintained in an inclined position as indicated in Fig. 3. Spacing sleeves 49 are interposed between the upper face of the supporting bar 46 and a front paper table 50, whereas screws 51 pass through said sleeves and engage the paper table 50 to fixedly support it in place, as represented in Fig. 3. From this figure it will be seen that the paper table 50 is arranged

substantially tangential of the platen at the front thereof where work sheets supported on said paper table may pass around the platen into the channel 15 and be held in a bent condition snugly against the face of the platen at the printing line, as indicated in Fig. 5. In order to support the pack of work sheets in this position, and in a fixed relation to the printing line, indicated by the arrow *a* in said figure, I provide the devices which will now be described.

The paper table 50 is provided with upright slots 52 therein to receive supporting and guiding means provided on two slides 53. This is in order to guide said slides in their adjustment towards and from the platen. These slides are alike in construction and the description of one will suffice for both. Each plate-like slide 53 is provided with a depending under-cut stud 54 (see Fig. 6) adapted to extend through the companion slot 52 in the paper table to guide the slide along said slot and provide against an accidental detachment of the slide from the paper table 50. A headed screw 55 carries an off-set pin 56. The stem of this screw and the off-set pin 56 pass through the associated slot 52 in the paper table and prevent a turning movement of the screw. The stem of this screw and also the pin 56 likewise extend through openings in the companion slide 53. A thumb nut 57 engages the threaded end 100 of the screw 55 and at its lower end bears against the associated slide or plate 53 thus binding it in its adjusted position when the thumb nut 57 is tightened. A backing up of the thumb nut releases the slide and permits it to be adjusted up and down on the paper table.

Each slide 53 is provided with an impaling pin 58 projecting forward from the face thereof and adapted to be received in openings in the upper edge portions of the work sheets 14, and thus support them at their upper ends on the paper table 50. The work sheets are thus supported in a pack of twelve or fifteen sheets in superposed relation and in exact registration, it being understood that both of the slides 53 are adjusted up or down to the same height, as indicated in Fig. 1 of the drawings. The work sheets 14 are preferably ruled horizontally and provided with vertical columns for filling in various data under captions at the heads of said columns such as "Piece work", "Day work", "Cash allowance", "Bonus", "Over time allowance", "Total", etc., etc. The intent in the present instance is to provide a monthly or weekly record on each horizontal line of each work sheet. At the end of each month or week, the entry on the various work sheets will be made on a given line, the next entry being at the end of the next month or week and so on.

In order to facilitate the proper adjustment of the slides 53 towards or from the platen so as to bring the proper line on each work sheet to position at the printing line, I have provided a scale or series of indices for each slide, so that the slides may be successively registered with successive indices on the scale and thereby quickly position the slides to the proper positions to receive the work sheets for any given month or week. The markings or indices on each scale are indicated at *b*, and an indicated mark or pointer *c* on each slide is adapted to register with the marks on the scale and thus indicate the proper positioning of the slides with reference to the scales.

In order to prevent an accidental detachment of the work sheets from the impaling pins 58 I provide the following devices on each slide. A

holding device designated as a whole by the reference numeral 59 is in the nature of a sheet metal slide movable up and down on its companion adjustable member or slide 53 into and 5 out of effective position, the former position being shown in full lines in Fig. 6, and the latter position in dotted lines in said figure. It will be seen from this figure that each slide 59 has an inclined contact face 60 adapted to overlap and coact with 10 the upper edge of the outermost sheet 14 on the pack of work sheets and to maintain it and the sheets beneath it from accidental detachment from the impaling pins. When, however, the slides 59 are moved upward to the dotted line 15 position represented in Fig. 6, the work sheets are free to be withdrawn from or placed on the impaling pins. I prefer to spring press these members 59 to effective position and therefore connect each of said members with a contractile 20 spring 61 anchored at one end on a pin 62 on the companion slide 53 and connected at its other end to an ear 63 on the companion holding member 59. Each holding member is held on its companion slide 53 and is guided and limited in its up 25 and down movements thereon, by two headed pins 64 secured to the slide 53 and the stems of which are received in a slot 65 in the companion locking member.

When impaling the work sheets on the pins 30 58, it may be found desirable to retain the locking members 59 in ineffective position, and I have therefore provided latching means for this purpose. Such latching means comprises a latch 66 pivoted at 67 on the companion slide 53 and having an engaging nose that is adapted to be received in a locking notch 68 in the companion locking member 59. When seated in the locking notch, the latch will retain the locking member in its uppermost, ineffective, position against 40 the force of the companion spring 61.

In the use of the construction of my invention a series of superposed work sheets 14 are impaled on the pins 58 and the slides 53 are adjusted to bring the requisite line for entry on said sheets 45 to the printing line. Assume, for example, the uppermost printed line beneath the printed headings on each work sheet is to be brought to the printing line, the slides 53 will be adjusted down to a corresponding position for this purpose and 50 secured in such position by tightening the thumb nuts 57. The writing of the single line entry will then be effected on the outermost work sheet of the pack. The entered sheet will then be removed and an entry made on the work sheet 55 beneath it, and so on until the pack of sheets is exhausted, when a new supply may be impaled on the pins 58. The next week's or month's entry will require an adjustment of the slides to the 60 next higher index mark on each scale and a pack of work sheets having been introduced in the machine and impaled on pins 58, the entries on the sheets may proceed as before.

It will be seen that the paper deflector 16 below the platen will receive the lower end portions of 65 the sheets of the pack and guide and maintain them in proper position whatever may be the positions of adjustment of the slides 53. Said deflector will also maintain the sheets at the lower end portions thereof in proper relation to the platen so that the deflector 16 in conjunction with the impaling pins 58 and the holding means for the top 70 of the work sheets will maintain said work sheets bent to conform to the surface of the platen and 75 maintain the sheets snugly against the front face

of the platen at and adjacent to the printing line for the proper entry of writing lines thereon.

In order to properly direct the lower end portions of the work sheets to the deflector 16 and prevent a lateral displacement of the pack with 80 reference to the paper table 50, I have provided side edge guides or gages 69 (see Figs. 1 and 3) which are secured to and project upwardly from the supporting bar 46 and coact with the pack of work sheets at each side of the paper table 50. These side edge guides or gages 69 are of sufficient 85 depth to coact with the side edges of the entire pack of work sheets and accurately maintain the sheets against lateral displacement.

Various changes may be made in the construction without departing from my invention as it is defined in the accompanying claims.

What I claim as new and desire to secure by Letters Patent is:

1. The combination of a cylindrical platen, a paper table fixed at the front of the platen, work sheet or card impaling pins carried on said paper table, and of a character to receive a plurality of work sheets or cards, means for affording an adjustment of said impaling pins towards and 90 from the platen to any one of a plurality of line space positions corresponding to the months or weeks of a year and on which pins may be impaled the upper ends of a plurality of work sheets or cards to be held in place thereby while the 95 work sheets or cards are being written, and a paper apron arranged beneath the platen and maintained spaced apart therefrom to receive the lower end portions of said plurality of work sheets or cards introduced downwardly and rear- 100 wardly from the front of the platen, the relation of the said paper table and apron being such that a thick pack of work sheets or cards may be maintained in a bent condition in conformity 105 with the surface of the platen at and near the 110 printing line to receive the impress of the types.

2. The combination of a cylindrical platen, a fixed paper table at the front of the platen, work sheet or card impaling pins carried by said paper table, means for affording an adjustment of said 115 impaling pins on said paper table towards and from the platen to any one of a plurality of line space positions corresponding to the months or weeks of a year, the construction and arrangement of the parts being such that the upper ends 120 of a plurality of work sheets or cards may be impaled and supported on said pins, a paper apron arranged beneath the platen and maintained spaced apart therefrom to receive the lower end portions of said plurality of work sheets, the relation of the said paper table and apron being such that a thick pack of work sheets introduced down- 125 wardly and rearwardly from the front of the platen may be maintained in a bent condition in conformity with the surface of the platen at and near the 130 printing line to receive the impress of the types, and releasable holding means for holding the work sheets impaled on said pins and against accidental detachment therefrom.

3. The combination of a cylindrical platen, a fixed paper table at the front of the platen, work sheet or card impaling pins carried by said paper table, means for affording an adjustment of said 140 impaling pins towards and from the platen to any one of a plurality of line space positions corresponding to the months or weeks of a year 145 the construction and arrangement of the parts being such that the upper ends of a plurality of work sheets or cards may be impaled and supported on said pins, a paper apron arranged be- 150

- neath the platen and maintained spaced apart therefrom to receive the lower end portions of said plurality of work sheets introduced downwardly and rearwardly from the front of the 5 platen, the relation of said paper table and apron being such that a thick pack of work sheets may be maintained in a bent condition in conformity with the surface of the platen at and near the printing line to receive the impress of the types, 10 and releasable holding means for holding the work sheets impaled on said pins and against accidental detachment therefrom, said holding means being movable to and from effective position and spring pressed to effective position. 15 4. The combination of a cylindrical platen, a paper table at the front of the platen, paper or card impaling pins carried by and adjustable on said paper table towards and from the platen and on which may be impaled the upper ends of a 20 plurality of work sheets or cards, a paper apron arranged beneath the platen and maintained spaced apart therefrom to receive the lower end portions of said plurality of work sheets, the relation of the said paper table and apron being such 25 that a pack of work sheets may be maintained in a bent condition in conformity with the surface of the platen at and near the printing line to receive the impress of the types, releasable holding means for holding the work sheets impaled 30 on said pins and against accidental detachment therefrom, said holding means being movable to and from effective position and spring pressed to effective position, and latching means for holding said holding means in ineffective position 35 against the force of the springs therefor and to facilitate the impaling of a pack of work sheets on said pins. 5. The combination of a cylindrical platen, a fixed paper table at the front of the platen, paper 40 or card impaling pins carried by said paper table, means for affording an adjustment of said impaling pins towards and from the platen, the construction being such that the upper ends of a plurality of work sheets or cards may be impaled and 45 supported on said pins, a paper apron arranged beneath the platen and maintained spaced apart therefrom to receive the lower end portions of said plurality of work sheets, the relation of the said paper table and apron being such that a 50 pack of work sheets may be maintained in a bent condition in conformity with the surface of the platen at and near the printing line to receive the impress of the types, and indices on said paper table for locating said impaling pins 55 at different line space points of adjustment towards and from the platen, thereby determining the positions where successive writing lines are to appear on the work sheets corresponding to entries for the weeks or months of a year. 60 6. The combination of a cylindrical platen, a fixed paper table at the front of the platen, slides carried by said paper table, means for affording an adjustment of said slides towards and from the platen, work sheet impaling pins carried by 65 said slides and constructed to receive and support a stack of work sheets, scales on said paper table with which said slides coact to indicate the positions of adjustment thereof and the writing line positions on the stack of work sheets im- 70 paled on said pins and corresponding to entries for the weeks or months of a year, and holding and guiding means arranged beneath the platen to receive the lower end portions of the stack of work sheets impaled on said pins, the relation of 75 said paper table and holding means being such that a stack of work sheets may be maintained in a bent condition in conformity with the surface of the platen at and near the printing line to receive the impress of the types. 80 7. The combination of a cylindrical platen, a paper table at the front of the platen, slides carried by said paper table, means for affording an adjustment of said slides towards and from the platen, work sheet impaling pins carried by said slides and of such construction as to receive a stack of work sheets, scales on said paper table with which said slides coact and of such a character as to indicate the positions of adjustment of the impaling pins and the writing line positions 85 on the work sheets impaled on said pins corresponding to the weeks or months of a year, holding and guiding means arranged beneath the platen to receive the lower end portions of a plurality of work sheets, the relation of said paper table and holding means being such that a pack of work sheets may be maintained in a bent condition in conformity with the surface of the platen at and near the printing line to receive the impress of the types, and releasable holding means for holding the work sheets impaled on 90 said pins and against accidental detachment therefrom. 95 8. The combination of a cylindrical platen, a paper table at the front of the platen, slides carried by and adjustable on said paper table towards and from the platen, work sheet impaling pins carried by said slides, scales on said paper table with which said slides coact to indicate the positions of adjustment thereof and the writing line positions on the work sheets impaled on said 100 pins, holding and guiding means arranged beneath the platen to receive the lower end portions of a plurality of work sheets, the relation of said paper table and holding means being such that a pack of work sheets may be maintained in a bent condition in conformity with the surface of the platen at and near the printing line to receive the impress of the types, and releasable holding means for holding the work sheets impaled on 105 said pins and against accidental detachment therefrom. 110 9. The combination of a carriage, a cylindrical platen carried thereby, a cross bar arranged above the platen and detachably connected at its ends to the carriage, a paper table secured to said cross bar and fixedly arranged substantially tangential to the platen at the front thereof, slides mounted on said paper table for adjustment thereon towards and from the platen, impaling 115 pins carried by said slides and of such a character that a plurality of work sheets are adapted to be impaled and held in position while they have entries successively imprinted thereon, scales on the paper table with which said slides coact, 120 the character of the scales being such as to indicate the positions of adjustment of said slides for making entries for the different weeks or months of a year, the separation of the index marks on said scales corresponding to the separation of printed lines on the work sheets, and means for securing said slides in the different 125 positions to which they may be adjusted. 130 10. The combination of a carriage, a cylindrical platen carried thereby, a cross bar arranged above 135 the platen and detachably connected at its ends to the carriage, a paper table secured to said cross bar and fixedly arranged substantially tangential to the platen at the front thereof, slides mounted on said paper table for adjustment thereon towards and from the platen, impaling pins carried by said slides and of such a character that a plurality of work sheets are adapted to be impaled and held in position while they have entries successively imprinted thereon, scales on the paper table with which said slides coact, 140 the character of the scales being such as to indicate the positions of adjustment of said slides for making entries for the different weeks or months of a year, the separation of the index marks on said scales corresponding to the separation of printed lines on the work sheets, and means for securing said slides in the different 145 positions to which they may be adjusted. 150

- the platen and detachably connected at its ends to the carriage, a paper table secured to said cross bar and fixedly arranged substantially tangential to the platen at the front thereof, slides mounted 5 on said paper table, means for affording an adjustment of said slides towards and from the platen, impaling pins carried by said slides and of such a character that a plurality of work sheets are adapted to be impaled and held in position 10 while they have entries successively imprinted thereon, scales on the paper table with which said slides coact, the character of the scales being such as to indicate the positions of adjustment of said slides for making entries for the different 15 weeks or months of a year, the separation of the index marks on said scales corresponding to the separation of printed lines on the work sheets, means for securing said slides in the different positions to which they may be adjusted, and releasable holding means carried by said slides for holding 20 work sheets impaled on said pins and against accidental detachment therefrom.
11. The combination of a carriage, a cylindrical platen carried thereby, a cross bar arranged above the platen and detachably connected at its ends to the carriage, a paper table secured to said cross bar and arranged substantially tangential to the platen at the front thereof, slides mounted 25 on said paper table for adjustment thereon towards and from the platen, impaling pins carried by said slides and on which a plurality of work sheets are adapted to be impaled and held in position 30 while they have entries successively imprinted thereon, scales on the paper table with which said slides coact to indicate the positions of adjustment of said slides, the separation of the index marks on said scales corresponding to the separation of printed lines on the work sheets, means 35 for securing said slides in the different positions to which they may be adjusted, releasable holding means carried by said slides for holding work sheets impaled on said pins and against accidental detachment therefrom, said holding means comprising spring pressed slides movable to and from effective position and normally held by their springs in effective position where they have a 40 contactive engagement with the upper edge of the outermost work sheet of the pack on the impaling pins, and manually controlled latching means co-acting with said spring pressed slides to hold them in ineffective position against the force of their springs.
